UNITED STATES PATENT OFFICE.

HENRY BRUCE FURR, OF DAYTON, ILLINOIS.

ROLLING-DISK CULTIVATOR.

SPECIFICATION forming part of Letters Patent No. 769,822, dated September 13, 1904.

Application filed April 18, 1904. Serial No. 203,729. (No model.)

To all whom it may concern:

Be it known that I, HENRY BRUCE FURR, a citizen of the United States, residing at Dayton, in the county of LaSalle and State of Illinois, have invented certain new and useful Improvements in Rolling-Disk Cultivators; and I do declare the following to be a full, clear, and exact description of the invention, such as will enable others skilled in the art to 10 which it appertains to make and use the same.

This invention relates to rolling-disk cultivators.

The object of the invention is to provide a machine of this character whereby the soil 15 may be cultivated to a greater or less degree, as circumstances may require, and to provide means whereby the position or direction of the disks may be changed while the machine is in motion.

20 A further object is to provide means whereby the disks may be raised and lowered to regulate the cut of the same and to raise them above the ground.

With these and other objects in view the 25 invention consists of certain novel features of construction, combination, and arrangement of parts, as will be more fully described, and particularly pointed out in the appended claims.

30 In the accompanying drawings, Figure 1 is a side elevation of the machine constructed in accordance with the invention. Fig. 2 is a top plan view of the same. Fig. 3 is a rear view. Fig. 4 is a detail vertical transverse 35 sectional view on the line 4-4 of Fig. 1. Fig. 5 is a horizontal sectional view, taken above beams. Fig. 6 is a detail view similar to Fig. 4, showing a modified construction of the parts shown in that figure. Fig. 7 is a detail 40 sectional view of the lower end of a disk-standard, showing a modified means for connecting the hub of the disks to said standard. Fig. 8 is a detail horizontal sectional view 45 showing a double hub arranged on the lower end of a standard, whereby two disks may be carried by one standard. Fig. 9 is a detail vertical sectional view of the lower end of a standard and a disk-hub, showing the manner in which the same may be lubricated.

Referring more particularly to the drawings, 1 denotes a main frame, consisting of longitudinal side bars 2, the forward ends of which are secured to bars 3, which converge and are bolted to the inner end of a tongue 4. The rear ends of the side bars are connected by a cross-bar 5, on which is mounted the driver's and operator's seat 6. The rear ends of the converging bars 3 are bent inwardly at an angle to the front portions thereof, and to said rear ends is bolted a cross-bar 7, which extends between the side bars 2. To the cross-bar 7 are bolted downwardly-projecting brackets 8, in which are secured the upper horizontal portions of right-angularly bent axles 9, on the lower ends of which are formed 65 spindles on which are journaled the supporting-wheels 10. Suitable brace-bars 12 extend from the lower or spindle end of the axle to the frame 1 to securely brace and hold the axles against movement. On the inner end 70 of the tongue 4 is secured an upwardly-projecting bracket 13, in which is pivoted a doubletree 14, to the ends of which are pivoted short depending rods 15, to the lower ends of which are connected draft-chains 16, 75 which pass under grooved pulleys 17, journaled in hangers 18, secured to the outer ends of a transversely-disposed bracket 19, which is secured to the under side of the tongue 4. On the ends of the draft-chains 16 are connected swingletrees 20.

Arranged beneath the frame 1 are a pair of disk-supporting beams 21, which are adjustably secured to the lower ends of front and rear arched bars 22 and 23, the lower ends of which are bent outwardly at right angles and pass through clips 24, secured to the beams 21. Set-screws 25 are screwed through the clips 24 and engage the bent ends of the arches and hold the beams in their adjusted 85 positions thereon. The front arched bar 22 is secured directly to the forward ends of the beams; but the rear arched bar is secured to rearward extensions 26 of the beams, as shown.

95 The beams 21 are preferably in the form of an obtuse angle, and each consists of upper and lower flat parallel bars which are connected

together and spaced apart by bolts 27, on which are arranged sleeves 28. The forward ends of the beams are pivotally connected to the lower ends of upwardly and forwardly 5 curved bars or arms 28, which are connected at their upper ends to the ends of a yoke 29, which has at its forward end a universal-joint connection with an adjustable head 30, which is slidably mounted on an upright post or bar 10 31, secured at its upper end to the lower side of the tongue 4 and at its lower end to a bracket 32, which is bolted to the lower side of the tongue and to a transverse bar 33, secured between the converging bars 3 in rear 15 of the inner end of the tongue 4.

The head 30 consists of upper and lower blocks 34, having formed in their meeting faces at the rear end sockets 35, which are adapted to receive the ball member 36 of the 20 joint which is secured on the yoke 29. The forward portions of the blocks are provided with vertical alined holes, by which they are slidingly engaged with the post or standard 31. The blocks 34 are held together on the 25 post by a clip 37, on the forward side of which is formed a lug or nut having a vertically-disposed threaded aperture which is engaged with a vertically-disposed threaded rod or bolt 38, the upper end of which passes loosely 30 through a hole in the tongue 4 and has fixed thereon a beveled pinion 39. The lower end of the rod passes through the bracket 32 and has on its lower end a retaining - nut 40. Meshing with the pinion 39 is a similar pinion 41, fixed on the end of a rearwardly-extending inclined rod 42, the forward end of which is journaled in a bracket 43, secured to the tongue, and the rear end of which is suitably supported and provided with a crank- 45 handle 44. Upon the turning of the crank-rod 42 the threaded rod or bolt 39 will be turned, which will cause the head 30 to be moved up or down upon the post or standard 31, and thereby raise or lower the forward 50 end of the beams through the yoke 29 and curved bars 28, which connect this end of the beams 21 with the head 30.

In the forward end of each beam is journaled a downwardly-projecting vertical standard 55 45. In rear of the standards 45 are arranged similar standards 46, the upper ends of which are journaled in brackets which project laterally from the outer sides of each of the beams. Back of the standards 46 are arranged other standards 47, which are journaled in the beams 21. The standards 47 are similar to the first-mentioned standards except that they project to a considerable distance above the beams, as shown. In the rear ends 60 of the beams are journaled still another pair of standards 48, which are of the same construction as the standards 45 and 46.

On the lower ends of each of the standards 45, 46, 47, and 48 is fixed a horizontal bear-

ing or support 49, in each of which is journaled a revolving disk 50. These disks are arranged on the inner sides of the standards and bearings 49 and are preferably flat, having their outer edges beveled to an edge, as shown. On each of the standards 47 are arranged upper 65 and lower coiled springs 51 and 52, and on the upper ends of the standards are fixed crank-arms 53, which retain the springs in place. Above the standards 47 is arranged a curved bar 54, to which are fixed downwardly-projecting brackets 55, having forwardly-projecting right-angularly bent lugs 56, in which are formed openings through which are adapted to pass the upwardly-extended ends of the standards 47. The lugs 56 engage said standards 80 between the upper and lower coiled springs 51 and 52, as shown.

The curved bar 54 is slidably supported by hangers 57, which consist of inverted-T-shaped plates 58, arranged on one side of the bar, 85 and on said plates are rotatably mounted an upper grooved roller 59, which engages the upper edge of the bar 54, and two grooved rollers 60, which engage the lower edge of the bar, which connection permits said bar to slide 90 laterally in either direction. To the upper ends of the hanger-plates 58 are loosely connected links 61, the upper ends of which are connected to the forward ends of hand-levers 62, pivotally connected to the standard 63 of 95 segmental rack-bars 64, which are mounted on and securely braced to the cross-bar 7 of the main frame. The segmental rack-bars 64 are further braced and connected together by a cross-bar 65, which rotatably supports the 100 rear end of the inclined crank-rod 42. The hand-levers 62 are provided with retaining-paws 66, which engage the rack-bars 64 and hold said levers in their adjusted positions. The bar 54 yieldingly supports the rear ends 105 of the beams 21 through the brackets 55, which engage the same between the springs 51 and 52. Upon the operation of the hand-levers said rear ends may be raised and lowered, as will be understood.

To each of the standards 45, 46, 47, and 48, between the upper and lower bars of the beams 21, are respectively connected crank-arms 67, 68, 69, and 70. The crank-arms 67 and 68 of the standards 45 and 46 are respectively connected to the crank-arms 69 of the standard 47 by links 71 and 72, while the crank-arm 70 of the standard 48 is connected by a link 73 to a second crank-arm 74, fixed on the standard 47. By the arrangement of crank-arms and links as just described it will be seen that the disk-standards of each beam are connected to the extended standards 47 to be turned thereby in unison.

In order that the standards 47 may be actuated to turn the other standards, the crank-arms 53, fixed on the upper end thereof, are connected by a cross-bar 75, to the center of

which is pivotally connected a longitudinally-disposed lever 76, the forward end of which is slotted and has a loose pivoted connection with the front arched bar 22. The rear ends of the lever 76 is adapted to slide on the rear arch 23 and is connected to a cable 77, which extends laterally in each direction and passes downwardly over grooved guide-pulleys 78, journaled on the rear side of the rear arch 23. The lower ends of the cable 77 are adjustably connected to foot-levers 79, the forward ends of which are pivotally connected to the sides of the front arched bar 22. The levers 79 are bent or curved laterally for a short distance to avoid interference with other parts of the machine, and the outer ends of the same pass through a guideway formed by the sides of the rear arched bar 23 and a rod or bar 80, arranged adjacent to and secured at its upper and lower ends to said sides. By depressing one or the other of the foot-levers the lever 76 will be actuated to cause the bar 75 to turn the crank-arms 53 and the standards 47, and through which motion will be imparted to the other standards to turn the disks carried thereby in one direction or the other to cause the soil to be thrown toward or from the corn.

In Fig. 6 of the drawings is shown a modified construction of the hangers 57 and the parts connected thereto. In this instance a hanger 81 is provided, said hanger having two pairs of grooved rollers 82 and 83, the former being arranged below, the latter above, a round bar 84, which is adapted to take the place of the bar 54 (shown in the other figures) and is curved to correspond with said bar 54. Below the bar 84 and spaced from the same is arranged a parallel bar 85, the ends of which are bent upwardly and secured to the ends of the bar 84. To the bar 85 is loosely connected, as by pairs of short links 86, the upper ends of downwardly-extending bars 87, which take the place of the brackets 55 and are provided at their lower ends with right-angularly bent apertured lugs 88, through which are adapted to pass the upper ends of the standards 47, as shown and described in connection with the lugs 56 on the brackets 55. The hangers 81 have each pivotally connected thereto the lower ends of a link 89, the upper ends of which are bifurcated, as shown, and are adapted to be pivotally connected to the operating-handles 62 to take the place of the links 61.

In Fig. 7 of the drawings is shown a detail vertical sectional view of the lower end of a disk-standard illustrating a modified construction of bearing for the disk-hubs. In this instance instead of the lower end of the standard and the bearing being cast in one piece said lower end of the standard is split upwardly a short distance, and said split ends are then bent laterally, as at 90, to form the

upper portion of the bearing and laterally-projecting ears or lugs 91, to which are bolted the laterally-projecting ears or lugs 92 of a casting 93, forming the lower part of the bearing.

In Fig. 8 is shown a double form of hub 70 94, by which two disks may be mounted on the lower end of a standard, it being sometimes desirable to use this arrangement of disks on the two outer or rear standards 48. In this form of hub the two disks mounted 75 thereon are disposed at an angle to each other, with their forward edges touching.

In Fig. 9 is shown an arrangement which may, if desired, be applied to the disk-standards, whereby the bearings on the lower ends of 80 the same may be lubricated. This arrangement consists in providing hollow or tubular standards closed at their upper ends by a threaded plug 91'. Within the standards is disposed a plunger or piston disk 92', having a 85 threaded aperture 93', said disk being mounted on a threaded rod 94', which projects down into the tubular standard and is screwed through the threaded aperture of the plunger-disk 92'. The upper end of the rod 94' passes through 90 an aperture in the plug 91' and is provided above and below said plug with stop-pins 95, whereby the rod is held from vertical movement, but is permitted to turn freely in the plug. On the upper end of the rod 94' may 95 be formed a suitable handle for turning the same. The plunger-disk 92' is provided on one edge with a notch 96, which is adapted to engage a vertically-disposed rib 97, formed on the inner wall of the tubular standard, 100 thereby preventing said disk from turning with the rod, but permitting the same to be screwed up or down by reason of its threaded engagement with the rod. In the tubular standard below the plunger-disk is placed 105 grease or other suitable lubricant, which when the plunger-disk is screwed down will force said lubricant through a feed-opening 98 in the hub of the disk, and thereby lubricate the same.

In the drawings each beam 21 is shown as having mounted therein four disk-standards. I do not, however, wish to confine myself to this number, as it is obvious that the length of the beams may be increased and any desired 115 number of disk-standards arranged therein, the same number being arranged in each beam.

I do not desire to limit myself to the use of my improved devices hereinbefore described in connection with a wheel-cultivator, as the same may be also used in connection with a walking-cultivator.

From the foregoing description, taken in connection with the accompanying drawings, the construction and operation of the invention will be readily understood without requiring a more extended explanation.

Various changes in the form, proportion,

and the minor details of construction may be resorted to without departing from the principle or sacrificing any of the advantages of this invention.

Having thus described my invention, what I claim as new, and desire to secure by Letters Patent, is—

1. In a machine of the class described, the combination with supporting-wheels of a main frame fixed to the axles of said wheels, a tongue connected to the forward end of said frame, beams adjustably supported beneath said main frame, curved upwardly-projecting bars pivotally connected to the forward ends of said beams, a yoke connecting the upper ends of said bars, a vertically-adjustable head having a universal joint connection with said yoke, means for adjusting said head to raise or lower the forward ends of said beams, means for raising the rear ends of the same, standards pivotally mounted in said beams, disks revolvably mounted in the lower ends of said standards and means whereby the angle of said disks may be changed, substantially as described.

2. In a machine of the class described, the combination with supporting-wheels of a main frame fixed to the axles of said wheels, a tongue connected to the forward end of said frame, beams adjustably supported beneath said main frame, means for raising the forward ends of the said beams, vertically-disposed standards mounted to turn in said beams, one of said standards in each beam extending upwardly and having fixed thereon a crank-arm, upper and lower coiled springs arranged on said extended standards, a curved bar arranged above the same, brackets extending downwardly from said bar and loosely engaging said standards between said springs, whereby the rear ends of said beams are yieldingly supported, hangers slidingly connected to said bar, hand-levers mounted on said main frame and having a loose connection with said hangers, whereby the rear ends of said beams may be raised or lowered, disks revolvably connected to the lower ends of said standards and means whereby the angle of said disks is changed, substantially as described.

3. In a machine of the class described, the combination with supporting-wheels of a main frame fixed to the axles of said wheels, a tongue connected to the forward end of said frame, beams adjustably supported beneath said main frame, means for independently raising and lowering the front and rear ends of said beams, vertically-disposed standards mounted to turn in said beams, two of said standards being extended above said beams, crank-arms fixed on the upper ends of the same, a cross-bar connecting said crank-arms, a pivoted lever connected to said cross-bar, a cable connected to the end of said lever, pivoted foot-levers connected to the ends of said cable upon the de-

pression of which the first-mentioned lever will be actuated to turn said extended standards, cranks fixed to the lower portion of said extended standards, similar cranks fixed to the other of said standards, links connecting the latter cranks with the cranks on said extended standards whereby upon turning the same motion will be imparted to all of the standards, bearings formed on the lower ends of the standards and disks revolvably mounted in said bearings, substantially as described.

4. In a machine of the class described, the combination with supporting-wheels of a main frame fixed to the axles of said wheels, a tongue connected to the forward end of said frame, beams adjustably supported beneath said main frame, front and rear arched bars arranged beneath said main frame, the beams adjustably connected to the lower ends of said arched bars to be moved laterally toward and from each other, upwardly-projecting forwardly-curved arms pivotally connected to the forward ends of said beams, a yoke connecting the upper ends of said arms, a head having a universal connection with said yoke, and a vertically-adjustable connection with said tongue, a clip engaging said head, a threaded lug formed on said clip, a threaded rod or bolt rotatably mounted in said tongue and engaging said threaded lug, means whereby said rod or bolt is rotated to screw said lug up or down and thereby raise or lower said head and the ends of the beams carried thereby, means for raising and lowering the rear ends of said beams, standards revolvably mounted in said beams, disks revolvably mounted on the lower ends of said standards, and means whereby said standards are turned to change the angle of said disks, substantially as described.

5. In a machine of the class described, the combination with supporting-wheels of a main frame fixed to the axles of said wheels, a tongue connected to the forward end of said frame, beams adjustably supported beneath said main frame, front and rear arched bars arranged beneath said main frame, said beams being adjustably connected to the lower ends of said arched bars to be moved laterally toward and from each other, upwardly-projecting forwardly-curved arms pivotally connected to the forward ends of said beams, a yoke connecting the upper ends of said arms, a head having a universal connection with said yoke, and a vertically-adjustable connection with said tongue, a clip engaging said head, a threaded lug formed on said clip, a threaded rod or bolt rotatably mounted in said tongue and engaging said threaded lug, a beveled pinion fixed on the upper end of said rod or bolt, a rearwardly-extending crank-rod rotatably supported above said main frame, a bevel-pinion fixed thereon and meshing with the pinion on said threaded rod or bolt, a crank fixed on the opposite end of said rod, whereby the same is

turned to rotate said threaded rod or bolt to screw said lug up or down and thereby raise or lower said head and the forward ends of said beams, means whereby the rear ends of 5 the beams are yieldingly supported, means for raising and lowering the same, standards revolubly mounted in said beams, horizontally-disposed bearings fixed to the lower ends of said standards, disks revolubly mounted in 10 said bearings, and means whereby said stand-

ards are turned in unison to change the angle of said disks while the machine is in motion, substantially as described.

In testimony whereof I have hereunto set my hand in presence of two subscribing witnesses. 15

HENRY BRUCE FURR.
